UNITED STATES PATENT OFFICE.

WILLIAM SNEE, OF PITTSBURG, ASSIGNOR TO CHARLES T. RUSSELL, OF ALLEGHENY, AND WILLIAM GUCKERT AND WILLIAM SMITH, BOTH OF PITTSBURG, PENNSYLVANIA.

HYDROCARBON-BURNER.

SPECIFICATION forming part of Letters Patent No. 404,804, dated June 4, 1889.

Application filed February 26, 1889. Serial No. 301,235. (No model.)

To all whom it may concern:

Be it known that I, WILLIAM SNEE, a citizen of the United States, and a resident of Pittsburgh, in the county of Allegheny and State of Pennsylvania, have invented certain new and useful Improvements in Hydrocarbon-Burners; and I do hereby declare that the following is a full, clear, and exact description of the invention, which will enable others skilled in the art to which it appertains to make and use the same, reference being had to the accompanying drawings, which form a part of this specification.

This invention relates to hydrocarbon-burners adapted to burn crude petroleum for generating steam in boilers of locomotive or stationary engines; and it consists in the improved construction of the fire-box and in the combination, with the fire-box, of valves for feeding air to the combustion-chamber, and thereby regulate in a simple and expeditious manner the amount of heat.

On the accompanying drawings I have shown my invention as applied to the boiler of a locomotive, showing the boiler and fire-box of the same.

Figure 1 represents a longitudinal sectional view, on a vertical plane, of a locomotive-boiler and fire-box, according to my improved construction; and Fig. 2 is a view from the under side of the fire-box, showing the circular valves and the levers for operating the same.

Like letters of reference denote corresponding parts in both the figures.

Reference being had to the drawings, the letter A designates the boiler, which is provided with the usual flues B, of any approved construction and arrangement.

C is the fire-box, inside of which I place a combustion-chamber D of the peculiar shape and construction shown in the drawings. This combustion-chamber consists of a hood E, of a width corresponding to the width of the fire-box and extending from one side of the same to the other. I prefer to make this hood of iron or other suitable metal, with a hollow space inside, which is filled with fire-clay

or other refractory material capable of withstanding intense heat. This hood forms a 50 crown or arch F immediately above the burner G, and is then bent in a downward and forward direction, as clearly illustrated on the drawings, extending toward the front part of the fire-box.

Below the forward part of this hood and in front of the burner is placed a deflector H, made of the same material as the hood proper and operating in conjunction with the forward part of the same to form a contracted 60 mouth-piece, as shown at I. This deflector H also extends clear across the fire-box from one side to the other, thus forming, in conjunction with the hood, the dome-shaped combustion-chamber D, provided with the oblong 65 outlet or mouth-piece I.

The burner (shown at G) may be of any approved construction adapted to burn crude petroleum, either by itself or in conjunction with a jet of steam. The fuel is fed to it by 70 means of a feed-pipe J, provided with a suitable valve or valves, and bent at right angles, as shown at J', its upper end being connected to a suitably-located tank or reservoir containing the liquid fuel. If the burner is 75 designed to burn hydrocarbons mixed with steam, the steam-pipe may be conveniently located inside of the feed-pipe J, so as to heat the hydrocarbon as it passes up into the burner. I desire the same to be understood, 80 however, that I do not limit myself to any particular type or construction of burner, as my invention consists not in the construction of the burner itself, but in the construction and combination of parts of the combustion- 85 chamber and air-valves.

The bottom of the combustion-chamber D is perforated, and covered on its under side by a circular disk K, having apertures k registering with the apertures in the bottom of the combustion-chamber. This apertured disk K has a central opening through which pipe J is inserted, so that said pipe will form a spindle or journal for the disk, around which it may be turned. The periphery of 95 the disk is supported by and slides in an an-

nular flange L, fastened to the under side of the fire-box and overlapping the under side of the movable valve-disk K.

The central part of disk K is provided with 5 a downwardly-projecting sleeve or collar M, which turns upon that part of pipe J inserted through it, and is provided with a lever N, projecting in front of the fire-box, and having a handle whereby it may readily be manipulated by the fireman or engineer in charge.

Another valve K', of precisely similar construction, is located in the bottom of the fire-box immediately in front of the opening or 15 outlet I of the combustion-chamber, and is manipulated by means of the handle or lever N'. If desired, additional valves for regulating the supply of air to the fire-box may be located in the front wall of the latter, as 20 indicated at O and P.

In some cases it may be desirable to provide the fire-box back of the combustion-chamber D with a transverse breast-wall Q, for the purpose of deflecting the products of 25 combustion over the top of the same before reaching the flues. This, however, is not essential.

The operation of this apparatus is as follows: After the oil has been turned on and is 30 ignited in the burner in the usual manner, the valve K is so adjusted as to feed a sufficient quantity of air into the combustion-chamber to generate heat enough to vaporize the oil. After a little while the hood E F will 35 be raised to a very high temperature by the combustion of the gases with which it is filled, and by now closing or partially closing the bottom valve K, at the same time opening valve K', the gas which is generated within 40 the combustion-chamber, and therein superheated to a temperature considerably beyond the explosion-point, will ignite on being supplied with air enough, through valve K', to permit of combustion. Thus a flame of intense heat will issue from the outlet I, which, 45

by impinging upon and curving around the dome F of the combustion-chamber, will maintain the heat within said chamber, thereby maintaining a constant supply of gas from the burner. By judiciously regulating the 50 supply of air through the valves K and K', and the auxiliary valves O and P when the latter are used, the temperature within the fire-box may readily be regulated at will, and by closing all the valves the fire will be extinguished in a moment. 55

Having thus described my invention, I claim and desire to secure by Letters Patent of the United States—

1. In a boiler-furnace provided with a fire-box, the combination of the fire-box, the dome-shaped hood within the same bent downwardly and forwardly at its front side, the deflector arranged below the forward part of the hood, and the burner located below the 65 arched top and within the hood, substantially as and for the purpose shown and set forth.

2. In a boiler-furnace provided with a fire-box, the combination of the exterior fire-box communicating with the flues of the steam-generator, the combustion-chamber located within the fire-box having an arched or dome-shaped top and narrow mouth or outlet facing the front end of the fire-box, the burner located within the combustion-chamber below 75 its arched top and back of its outlet, the air-valve in the bottom of the combustion-chamber encircling the burner, and the bottom valve in the fire-chamber outside of the combustion-chamber, but below the outlet of the 80 same, substantially as and for the purpose shown and set forth.

In testimony that I claim the foregoing as my own I have hereunto affixed my signature in presence of two witnesses.

WILLIAM SNEE.
